UNITED STATES PATENT OFFICE.

ERLING CHRISTOPHERSEN, OF NEW YORK, N. Y.

ENGINE-EXHAUST MUFFLER.

1,356,696.

Specification of Letters Patent. Patented Oct. 26, 1920.

Application filed October 24, 1919. Serial No. 332,913.

To all whom it may concern:

Be it known that I, ERLING CHRISTOPHERSEN, a citizen of Norway, and a resident of New York city, State of New York, 5 United States of America, have invented certain new and useful Improvements in Engine-Exhaust Mufflers; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

The present invention relates to mufflers for exhaust gases, and particularly used to muffle or silence the exhaust of gas engines, such, for example, as automobile engines. 20 It embodies means for subdividing the gases into a large number of jets radial, or substantially so, to the direction of movement of the gases in the exhaust pipe, and combines the jets after decreasing their heat 25 content into a spirally enlarging channel terminating in an outlet to the atmosphere.

The most successful muffler embodying these means now on the market can take care of but a limited quantity of gases, and 30 while it is ample and adequate for the small engines, usually of four cylinders, of moderate priced cars, it will not take care of the gas of the larger cars, of six, eight and twelve cylinders.

It was at first thought that simply increasing the dimensions of this known muffler, using the same construction, would meet the requirements of larger automobile engines, but this increase in size had to be 35 such that there was not sufficient clearance under the car, and the weight was unduly great.

The problem then was to take care of the increased quantity of gas, operating on the 40 same principle, and keep the dimensions and weight within the permissible limits; and this has been done in a most satisfactory manner in the present invention.

Notwithstanding these rigid requirements, 45 the parts have been limited to a few castings, interfitting, as will be hereinafter described, and fastened together by three bolts, all accessible from the outside.

The drawings presented herewith show 50 the construction at about two-thirds the actual size of the devices being sold. Like

parts are indicated by similar reference characters.

Figure 1 is a central section.

Fig. 2 is a plan view showing the interior 60 construction of one of the outer elements into which the end of the engine exhaust pipe is inserted.

Fig. 3 is a plan view showing the interior of the element coöperating with that of 65 Fig. 2.

Fig. 4 is a plan view showing the interior of the other outer element with the second interior element coöperating therewith partly broken away. 70

The muffler consists of an outer, substantially spiral member 1 on the inlet side of the muffler, and a second outer substantially spiral element 2 carrying the outlet orifice. Between these two elements 1 and 2, which 75 form a casing, are two sub-dividing elements 3 and 4 held in spaced relation to one another and to the outer elements.

One of these outer elements, for example the element 1, has a groove 5 in its edge into 80 which fits a tongue 6 on the other outer element, forming a joint that prevents the elements from slipping with respect to one another, when held together by three bolts 7.

The outer member 1 has a plate-like body 85 portion *a*, a marginal flange *b* and boss or tubular portion *c* into which loosely fits the end of the engine exhaust pipe, not shown. Bolt holes *d* are provided for the reception of the bolts 7. 90

The interior of the outer member 1 is provided with a number of vanes 8, arranged radially around the eccentrically arranged inlet *c*, these vanes increase in length as the spiral chamber B between the vanes and 95 wall or flange *b* enlarges in cross section to near the exit orifice, where one of the vanes 8^a is extended into a partition wall or rib 9.

Coöperating with the member 1 is the member 3, Fig. 3, having an eccentrically 100 arranged flared opening 10 directed toward the inlet for gases. This opening is smaller than the tubular portion *c* of member 1. This member 3 is of spiral shape and its periphery is spaced from flange *b* of member 105 1 to form a gas passage, as indicated at *e* Fig. 1, and has notches 11 partly surrounding or embracing the three bolts 7 holding the parts together.

Both sides of the member 3 are provided 110 with vanes that taper in two directions. The concave portion of the side has straight

radial vanes 12 concentric with the flared opening 10 and increasing in length from the center of the spiral toward the discharge to correspond with the ribs 8 on element 1, 5 with which they alternate. One of the vanes 12^a is extended to form a partition rib extending across the wider end portion of the spiral channel B, which is of increasing width in member 1 and separates the 10 wide and narrow ends. This partition prevents the major portion of the gases from following along the channel and causes them to pass over the edge of member 3 to a central discharge chamber A between members 15 3 and 4.

The member 3 terminates in a curved concave tongue 13 extending into the exit opening. This tongue has, preferably, but not necessarily, a small strengthening rib 13^a 20 extending from the rib 12^a to the end of the tongue. On the opposite side of member 3 is a second set of vanes 14 arranged around the opening 10 on that portion f of the member 3 that is curved convex toward the center of the muffler. These vanes 14 are in general radially directed, but curved or spirally shaped in the direction of the passage of the gases through the discharge chamber A, between the members 3 and 4. 30 One of these ribs or vanes is extended into a partition wall 15 at the tongue 13 and causes the gases to follow the spiral chamber A inside the member 3 between the ribs 14 and the rim of the member 3 from its narrowest to its widest portion at the tongue 13 and the smaller end of chamber A.

Interfitting and alternating with the spiral ribs 14 is a like series of ribs 16 on the spiral member 4, Fig. 4, around a central opening 17 that is larger than the opening 10 in member 3.

This member 4, like member 3, is concave at its outer portion g and concave at h near the opening 17, corresponding to member 3, thus forming the central discharge chamber A, Fig. 1.

The periphery of the member 4 is also provided with notches 18 to permit the passage of the bolts 7. At the narrower portion of the spiral passage formed by the concave portion g is a short partition rib 19. On the opposite side of this member 4 is a set of vanes 20, radially arranged with respect to the opening 17, and similar to the vanes 12 on member 3. These vanes, like vanes 12, increase in length as the spiral chamber C between their ends and outer member 2 increases in cross section, the vane near the discharge opening being extended 60 into a partition 21.

The other outer member 2 is provided with a cone 22 directed in alignment with the co-axially arranged openings, e, 10, and 17, and this cone has surrounding it radial 65 vanes 23 increasing in radial width and

tapering in two directions to correspond to and alternate with the similar vanes 20 on member 3. These vanes are on the flat body portion k of the member 2 that has a marginal flange l carrying the bead 6 and has the outlet 24 for the gases. The flange l has a rib extension 25 that connects with a partition rib 26 forming an extension of one of the radial vanes 23 on the portion k.

The outer member 1 has a pair of securing members 27 and 28, each having a slot 32 forming one-half of a bolt-hole. These slots register with like slots 32 in the securing members 29 and 30, respectively on the other outer member 2 when the members 30 are secured together by the bolts 7. Through the holes 32 thus formed are passed the bolts holding the muffler to the vehicle. Preferably, but not necessarily, each securing member has a slot in its side edge, as indicated at 33 Fig. 1, for additional bolts.

The bolts 7, preferably, are square just beneath their heads, and the holes in one of the outer members, for example the member 2, are also square to prevent the bolts from 90 rotating loose from the vibration of the vehicle.

The spiral vanes 14 and 16 are preferably but not necessarily less in number than the radial vanes 12 and 20, and do not fit so 95 closely together and are shorter in the axial as well as in the radial direction of the muffler.

As the gas stream enters at e it is subdivided into a plurality of concentric radially expanding portions, and each portion is peripherally divided into a large number of small streams or jets substantially radially directed. By reason of the larger spaces between the interfitting spiral ribs 100 14 and 16 the jets passing through the jet forming nozzles so formed are of lesser velocity than those passing through the other nozzles formed by the ribs or vanes 8 and 12, and 20 and 23, and are, besides, given 110 a spiral direction in the middle chamber A in the direction of the discharge outlet 24. The radial jets formed by the vanes 8 and 12 tapering in two directions discharge into the spiral chamber B at high velocity, pass 115 over the outer edge of the member 3 into the middle discharge chamber A, and while doing so are compelled to pass along the continually enlarging spiral chamber B by the rib 12^a closing the smaller narrow end of 120 this chamber toward the exit in discharge of the muffler.

The gases in the middle chamber A are directed in a similar spiral direction by ribs 15, 19, and 21 closing the smaller narrow end 125 of the middle discharge chamber A. The jets discharging between the vanes 20 and 23 into the spiral chamber C have high velocity, are compelled to take their spiral course by the rib 21 closing the smaller nar- 130

row end of the chamber C and direct the gases from one end of the chamber to the other, at the same time permitting their escape or discharge over the outer edge of member 4 into the middle discharge chamber A, where they meet the spirally directed jets discharging directly into chamber A from between the vanes 14 and 16, and are directed to the discharge 24 by the tongue 13, fully expanded to atmospheric pressure at high velocity and greatly cooled, so that the discharge is practically at atmospheric pressure and noiseless. In other words, the three chambers, A, B, C, are in axial alignment, and the two end chambers B and C discharge through the peripheral slot formed between the outer edges of the stationary members 3 and 4 into the central chamber A.

I claim—

20 1. In an engine exhaust muffler, means to sub-divide the gas-stream from the engine into a plurality of concentric parts, means for subdividing each part into a larger number of expanding jets and means permitting the discharge of the gases from said jets into a common discharge chamber.

25 2. In an engine exhaust muffler, means to sub-divide the gas-stream from the engine into a plurality of concentric parts, means for sub-dividing each part into a large number of expanding jets and means permitting the discharge of the gases from said jets into a common discharge chamber of increasing cross-sectional area.

30 3. In an engine exhaust muffler, means to sub-divide the gas-stream from the engine into a plurality of concentric parts, means for sub-dividing each part into a plurality of jets, the jets from each part discharging into a separate chamber and one of said chambers arranged to receive the gases from the other chambers and discharge the combined gases to the atmosphere.

35 4. In an engine exhaust muffler, means to sub-divide the gas-stream from the engine into a plurality of concentric parts, means to sub-divide each part into a plurality of jets, the jets from some of the parts discharging at high velocity into chambers corresponding to said parts, and the chamber receiving the discharge from the jets from one of the parts at lower velocity and also receiving the discharge from the other chambers and discharging the combined gases to the atmosphere.

40 5. In an engine exhaust muffler, means to sub-divide the gas-stream from the engine concentrically into a plurality of parts, means to sub-divide each part into substantially radial jets, the jets pertaining to each part discharging into a separate spiral chamber, one of said chambers arranged to receive the peripheral discharge of the other chambers and deliver the combined expanded gases to the atmosphere.

6. In an engine exhaust muffler, means to sub-divide the gas-stream from the engine into a plurality of concentric parts, radial means to sub-divide each part into jets, the jets from each part discharging radially into a separate spiral chamber of gradually increasing cross-section, the jets of one of the parts being directed spirally into its pertaining chamber and having less velocity than the jets pertaining to the other parts, said latter chamber also receiving the peripheral discharge from the other chambers and discharging to the atmosphere.

7. An engine exhaust muffler having an inlet and an outlet, a stationary chamber formed centrally in the casing and having a peripheral inlet slot through which exhaust fluid from axially disposed opposite ends of said chamber enter, said chamber discharging directly to said outlet at its larger end.

8. A muffler, comprising a casing having a gas inlet, a spiral chamber in the casing, and means whereby gas from the inlet enters said chamber both at the center and at the periphery thereof.

9. An engine exhaust muffler, comprising a casing having an axial gas inlet and means in the casing forming a plurality of chambers arranged side by side and communicating axially with said inlet, one of said chambers receiving the peripheral discharge of gas from the other chambers.

10. An engine exhaust muffler, comprising a casing having a gas inlet, means in the casing forming a central chamber and a chamber on each side of the latter communicating axially with said inlet, said side chambers communicating through their peripheries with the periphery of the central chamber.

11. In an engine exhaust muffler, a casing having an axial inlet for exhaust gases, means in the casing forming a central spiral chamber, a spiral chamber on each side of the central chamber communicating axially with said inlet, circularly disposed radial jet devices through which the gases are expanded in two directions and discharged into the respective chambers, said side chambers discharging peripherally into the central chamber.

12. In an engine exhaust muffler, a spiral member having a central inlet for engine gases and a similar member having a gas outlet near its periphery, both of said members having flanges around their sides capable of interfitting at their abutting edges to form a casing, the first mentioned member having radial vanes tapering in two directions, surrounding said inlet, a cone on the other member co-axial with said inlet, and radial vanes tapering in two directions surrounding said cone, a pair of co-operating members inclosed in said casing and

forming a central chamber spaced apart at their peripheries and having vanes coöperating with the vanes of the casing members, said coöperating members forming a spiral 5 central chamber receiving gases discharged from said radial vanes between their spaced edges and discharging said gases to the atmosphere.

13. In an engine exhaust muffler, four co-
10 axial members each formed as a separate casting and each having radially disposed vanes interfitting with the adjacent member or members, the two outer members having marginal flanges forming a casing inclosing
15 the other two members, said members constructed to receive gases at their center and discharge them between the interfitting vanes to peripheral chambers, one of said chambers operating as a discharge chamber and receiving the expanded gases from
20 the other chamber, and bolts passing from one outer member to the other and holding the parts assembled.

14. In an engine exhaust muffler, co-axial
25 spiral members each formed as a separate casting, the two outer ones of said members having marginal flanges abutting one another to form a casing, and each member having a circular row of vanes radially

disposed with respect to an inlet for engine gases on one of said outer members, the vanes of one member interfitting with the vanes of an adjacent member to form expanding nozzles through which the gases are radially discharged, spiral chambers at 35 the ends of said nozzles and formed by said members, one of said chambers discharging to the atmosphere and receiving gases expanded by said nozzles over its periphery.

15. In an engine exhaust muffler, co-axial 40 spiral members, the two outer members having marginal flanges abutting one another to form a casing and each member having vanes radially disposed with respect to an axial inlet opening in one of the outer members, said members forming spiral chambers between the outer ends of said vanes and the peripheries of the members, the chambers having a continuously increasing cross-section, ribs on said members closing 50 the smaller end of the chambers, one of said outer members having a discharge opening receiving gases from one chamber, which in turn receives expanded gases at its periphery.

In testimony that I claim the foregoing 55 as my invention, I have signed my name hereto.

ERLING CHRISTOPHERSEN.
